UNITED STATES PATENT OFFICE.

FRANK ENGEL, OF BUFFALO, NEW YORK, ASSIGNOR TO NATIONAL BATTERY COMPANY, OF BUFFALO, NEW YORK, A CORPORATION OF NEW YORK.

CASTING-MACHINE.

1,012,829.

Specification of Letters Patent. Patented Dec. 26, 1911.

Application filed March 15, 1909. Serial No. 483,510.

To all whom it may concern:

Be it known that I, FRANK ENGEL, a citizen of the United States, residing at Buffalo, in the county of Erie and State of New York, 5 have invented a certain new and useful Improvement in Casting-Machines, of which the following is a specification.

My invention relates to casting machines and the objects of the invention are, first, to 10 provide a machine adapted to both form the casting and remove the gate or sprue therefrom, second, to provide a construction such that the gates will be automatically sheared off as the mold is being opened. Third, to 15 provide means for ejecting the casting. Fourth, to provide means for clamping the parts of the mold tight shut with a minimum of friction. Fifth, to provide correlating means whereby the major portion of the operation of the machine may be accomplished 20 by the manipulation of a single lever. Sixth to provide advantageous details of construction which will be more fully pointed out in the following description and 25 claims.

In the form of machine selected to illustrate my invention: Figure 1 is a front elevation of the complete machine showing the same in closed position. Fig. 2 is an end elevation of the machine. Fig. 3 is a perspective view of the particular form of casting resulting from the form of mold chosen to illustrate the invention. Fig. 4 is a plan view of the complete machine showing the same in readiness to receive the molten metal. Fig. 5 is a sectional elevation on the line 5—5 Fig. 4. Fig. 6 is a perspective view of the particular form of the ejecting member used in the machine here illustrated. 40 Fig. 7 is a perspective view showing the ejecting cams and the bottom side of the plate or block which co-operates with said cams. Fig. 8 is a perspective view of the top of the mold used in this particular machine. Fig. 9 is a top view of the shearing cam and a portion of its operating lever.

Similar numerals refer to similar parts throughout the several views.

The mold 10 contains one or more mold 50 cavities for forming the castings 11, the number in the present design being five, as shown in dotted lines Fig. 4. The castings may assume various forms but for illustration I have selected a form adapted to be used as

a battery connector and having eyes 12 at 55 their ends as shown in perspective in Fig. 3.

The mold may be supported upon any suitable base, the base in the present form consisting of a foundation plate 13 to which are secured four standards 14 to which the 60 mold plate is bolted. In the present preferred design the mold is raised somewhat above the foundation plate to afford space for the ejecting mechanism hereinafter described.

The mold is adapted to be closed by a cover 16 which is hinged to the mold and is provided with gate apertures 17 through which the molten metal may be introduced into the mold. For convenience in pouring, 70 a basin or depression 18 is formed in the top of the cover surrounding the gates therein as best shown in Fig. 8. The cover is not only hinged to the mold so that it may be raised and lowered to open and close the mold but 75 is also laterally shiftable for shearing off the gate-metal after the casting has been formed. In the preferred construction the cover is provided with laterally extending hinge pins 20 adapted to both rotate and shift laterally within the apertured lugs 21. In the present instance these lugs are formed at the upper end of the hangers 22 bolted to the back of the mold as best shown in Fig. 5. By preference a counterweight 24 is attached 80 at the end of an arm 25 extending rearwardly from the cover 16 to serve as a counterbalance and hold it in open position indicated by dotted lines Fig. 2. It is desirable that the cover be provided also with a handle 90 26 for raising and lowering it.

The lateral shifting of the gated cover is effected by cam mechanism which in the type of machine chosen for illustration consists of a lever 30 rotatably connected to the mold 95 by means of a pin 31 securing into the mold. Rigidly secured to said lever is an eccentric or rotatable cam 32 adapted to contact one edge of the cover. In the arrangement illustrated, when the eccentric is rotated in an 100 anticlockwise direction the cover will be forcibly moved toward the left (Fig. 4) for shearing the gate metal from the castings. A cam surface 33 is formed on the edge of the cover opposite to eccentric 32 and is 105 adapted to be engaged by a pin 34 secured to the underside of the lever 30 as indicated in Fig. 4. The arrangement is such that

when the lever is rotated to the position shown in full lines in Fig. 4 it will shift the cover to the right to return it to normal pouring position. Said lever in this preferred form of machine performs the double function of shifting the cover sidewise and clamping it tightly in closed position. The clamping effect is obtained by means of a catch 35 rigidly secured to the mold and having its under surface downwardly beveled to engage and force the lever downwardly as the latter comes into contact with it. This catch is an inverted L shaped member, the portion overhanging the lever 30 as shown in Fig. 4, having its engaging underside beveled, as just stated. A raised boss 36 is by preference formed upon the top of the cover near the center thereof where it may be contacted by the lever just as the latter is about to be engaged by the catch 35. As a result of this construction the lever is freely rotatable until just prior to the moment when said lever comes forcibly into contact with the catch.

25 The ejecting means for removing the castings from the mold consists, in this the preferred form, of a block or plate 38 having cam surfaces 39 adapted to engage the cam surfaces 40 formed on the stationary hangers 22 and 41. For symmetry the hangers 41 are similar to the hangers 22, previously mentioned, and are bolted or otherwise secured to the edges of the mold as clearly shown in Fig. 5. By preference said 30 block is guided in its lateral movement by the stationary members 22 and 41. Loosely resting upon the block 38 is a plate 43 provided with ejector pins 44 adapted to engage the castings to lift them from the mold after they are finished. The ejector pins project up through the suitably apertured mold plate 10 and are vertically slidable therein, the result of this construction being that when the block is forced laterally 40 toward the highest portion of the cams 40 it will rise and force said plate and the ejector pins upward to eject the casting. Said plate is urged to descend to normal position by compression springs 45 interposed 45 between said plate and the mold 10. The ejector pins may assume various forms, their chief function being to eject the casting from the mold; but in the present construction said pins have an additional function, their heads being so shaped as to constitute a core for the eyes 12 at the ends of the castings. The heads on these particular pins are conically tapered, the smaller dimension lying at the top as clearly shown 50 in Figs. 5 and 6. As a result they will both form the eye and lift the casting after the latter is formed.

60 The preferred means for moving the block 38 horizontally to operate the ejector pins comprise a lever 46, pivoted at the sta-

tionary point 47 and connected to said block by means of a link 48.

In operation after the cover 16 has been swung down to closed position the lever 30 is rotated from the dotted position shown 70 at the right of Fig. 4 to the full line position shown at the left. This causes the cover to be shifted to the right, through the action of the pin 34 on the cam surface 33, where it will occupy the normal position for 75 pouring. This movement of the lever also causes it to become engaged by the lower beveled surface of the catch 35 which presses the lever down hard upon the boss 36 and holds the cover tightly in closed position. As a result the casting will be of proper thickness and moreover the formation of "fins" on the casting will be avoided. The mold is now ready to be poured, the ejector lever 46 occupying a position at 80 the right as indicated in full lines Fig. 4, and the ejector pins being in lowest position as shown in Fig. 5. In this particular construction the heads of the pins will lie within the mold cavity and constitute a 85 core for forming the apertures at the ends of the castings. After the metal has been poured into the depression 18 in the cover 16, and the molds have been filled and given time to cool, the lever 30 is swung to the 90 right which releases said cover and at the same time rotates the eccentric 32 in a direction to force said cover to the left to shear off from the castings that portion of the metal remaining within the gate apertures 100 17 and basin 18, the shearing edges being the metal surrounding the bottom of holes 17. It will be understood that my machine is best adapted for casting relatively soft metal such as lead and lead mixtures, and 105 no trouble is experienced for the leverage produced by the combined eccentric 32 and lever 30 is very large compared to the force exerted upon said lever.

110 By referring to Fig. 4 it will be seen that the boss 36 is approximately in a line between the pivot 31 and catch 35. The result is that the lever 30 leaves said boss about the same time that it leaves said catch and consequently after the lever has been 115 released from the catch there will be little or no friction upon the top of the cover. As soon as the gates have been sheared and the shearing lever 30 is back out of the way, the cover is thrown back and the ejector 120 lever 46 moved from the position shown in full lines Fig. 4 to the one shown in dotted lines. This causes the lateral movement of the block 38 toward the highest portions of the cams 40 which raises said 125 block and the ejector pins 44. The rise of said pins lifts the castings out of the mold, whereupon they may be removed by the operator. The ejector lever is then returned to normal position and the ejector pins are 130

again lowered by gravity and the action of the springs 45. The gates and metal remaining in the apertures 17 may be readily removed by inserting a punch or similar tool through the apertures 17 from the underside of the top, and the machine is then ready for a repetition of the operation.

What I claim as new and desire to secure by Letters Patent is:

1. In a casting machine, a mold and a gate member hinged thereto through which the molten metal may be introduced into the mold, said gate member being movable relatively to the mold for shearing off the gate-metal from the casting.

2. In a casting machine a mold, a cover hinged thereto having a gate through which the metal may be poured, and means for moving said cover transversely to said gate to shear the gate-metal from the casting.

3. In a casting machine, a part for containing the mold, a cover adapted to be raised from and lowered onto said mold containing part, said cover having an aperture through which the molten metal may be poured, and means for moving said cover transversely to its aperture for shearing off the gate-metal from the casting.

4. In a casting machine, a mold, a gate member hinged thereto and means for moving said gate member in the direction of the axis of its hinge.

5. In a casting machine, a mold, a gate member hinged thereto and a cam device for moving said gate member in the direction of the axis of its hinge.

6. In a casting machine, a mold, a gate member hinged thereto, a rotatable lever, and means operated by said lever for moving said gate member in the direction of the axis of its hinge.

7. In a casting machine, a plurality of parts adapted to contain the mold, one of said parts being hinged to another and movable laterally to shear off the gate-metal, and an eccentric for moving said hinged part laterally.

8. In a casting machine, a mold, a gate member hinged thereto, a rotatable lever, and means on said lever adapted to contact opposite edges of said gate member for moving it back and forth parallel to the axis of its hinge.

9. In a casting machine, a mold, a gate member hinged thereto and laterally movable thereon, a lever pivotally connected to said mold, an eccentric on said lever adapted to contact said gate member to move it laterally in one direction, and a cam surface on said gate member, adapted to be contacted by said lever to move said gate member laterally in the opposite direction.

10. In a casting machine, a mold, a cover hinged thereto, a boss on said cover a catch connected to said mold, and an arm piv-

totally connected to said mold and adapted to ride upon said boss to be engaged by said catch for wedging said cover in a closed position to prevent the formation of fins on the casting.

11. In a casting machine, a mold, a longitudinally sliding gate member hinged thereto, a lever pivotally connected to said mold, and a catch member connected to said mold and having a beveled surface adapted to engage said lever to force the same down upon said gate member for holding it in close contact with the mold.

12. In a casting machine, a mold, a gate member hinged thereto and laterally shiftable for shearing off the gate-metal, a lever adapted to move said gate member laterally, and a member rigidly connected to said mold and having a beveled surface adapted to engage said lever for clamping the gate member in closed position.

13. In a casting machine, a stationary mold, a sliding cover therefor having gate apertures through which metal may be introduced into the mold, and a clamping device comprising a lever having a stationary pivot and a stationary catch adapted to engage said lever to wedge the cover tightly closed.

14. In a casting machine a stationary mold, a laterally shiftable gated cover hinged thereto and means for shifting and for locking said cover in closed position, said shifting and locking means being hand operable from a single part thereof.

15. In a casting machine a stationary mold, a laterally shiftable gated cover hinged thereto and means for shifting and for locking said cover in closed position, said shifting and locking means including a pivoted lever, a plurality of cams operated thereby, and a catch adapted to engage said lever.

16. In a casting machine a mold, a cover therefor, a lever for holding the same closed, a pivot for said lever, a catch for holding it against the cover when closed, and a raised portion on said cover adapted to be contacted by said lever and being located approximately in line between the lever pivot and catch for the purpose described.

17. In a casting machine, a mold, a cover hinged thereto, a counterweight tending to raise said cover, a lever pivotally connected to said mold and adapted to swing over said cover, and a catch connected to said mold for holding the lever in close contact with said cover to hold the latter closed in opposition to the influence of said counterweight.

18. In a casting machine, a mold, a plurality of members adapted to simultaneously eject the castings therefrom, said members having portions forming the cores of the castings, and a hand operated cam device for operating said ejecting members.

19. In a casting machine, a mold, an ejecting member passing through said mold and slidably mounted therein, a block movable in the same direction as said ejecting member and also in a direction transverse thereto, cams for forcing said block in the direction of motion of said ejecting member, and other means for forcing said block transversely upon said cams.
- 10 20. In a casting machine, a mold, an ejecting member slidably mounted in said mold

for ejecting the casting therefrom, a block vertically and horizontally movable adapted to operate said ejecting member, cams for moving said block vertically and hand operated means for moving said block horizontally upon said cams. ¹⁵
